[57] CLAIM

The ornamental design for a housing for an audio connector, as shown and described.

DESCRIPTION

FIG. 1 is a top plan view of one embodiment of a housing for an audio connector showing our new design;

FIG. 2 is a bottom plan view thereof;

FIG. 3 a front elevational view thereof;

FIG. 4 is a rear elevational view thereof;

FIG. 5 is a left side elevational view thereof;

FIG. 6 is a right side elevational view thereof; and,

FIG. 7 is a top, front, right isometry view thereof.

The broken lines shown throughout the drawing figures are included for the purpose of illustrating environmental elements only and form no part of the claimed design.
